PUMP JACK

Ross T. Cruikshank, Minneapolis, Minn., assignor, by direct and mesne assignments, of forty-five per cent to Carl A. Anderson, Minneapolis, Minn., and ten per cent to Louis Wigen

Application March 1, 1946, Serial No. 651,359

6 Claims. (Cl. 74—25)

1

This invention relates to power jacks for longitudinally reciprocating a pump plunger or the like through application of either rotary or oscillatory power.

It is an object of the invention to provide a simple, compact and highly efficient pump jack or the like, driven from a source of rotary or oscillatory power and operative to apply straight line forces only, longitudinally of the reciprocable driven member.

A further object is the provision of a power jack of the class described for reciprocating piston rods and the like, whereby power is applied in both pulling and thrust strokes upon the reciprocable member in an even manner with the elimination of jerkiness and sharp pulsations.

A further object is the provision of a pump jack or the like which eliminates the use of pitman and walking beam principles and makes driving connection between the source of power and the reciprocable driven member through a novel and highly efficient gear mechanism.

These and other objects and advantages of the invention will be more apparent from the following description made in connection with the accompanying drawings, wherein like reference characters refer to the same parts throughout the several views and in which—

Fig. 1 is a front elevation of an embodiment of the invention applied to a vertical pump rod showing the working parts in the extreme elevated position of the pump rod;

Fig. 2 is a similar view showing the positioning of the parts in the intermediate position of the stroke of the pump rod;

Fig. 3 is a similar view showing the parts positioned with the pump rod at the lower end of its stroke;

Fig. 4 is a side elevation showing the mechanism positioned at the top of the pumping stroke; and

Fig. 5 is a cross section taken on the line 5—5 of Fig. 2.

In the form of the invention illustrated, the mechanism is mounted upon a suitable base 7, as shown, comprising a cap or head internally threaded to fit and be secured to the diminished upper end of a pump cylinder or well pipe 8. A pump or piston rod 9 is mounted for reciprocation in the cylinder 8 and has its upper end 9a suitably connected with a sliding cross head 10 which may be constructed in the form of a solid bar having vertical slide bearings drilled therein in its end portions, for reciprocation upon a pair of rigid, vertical guide rods 11, which are affixed at

2

their lower ends in sockets provided by the base member 7. A suitable packing gland 12 is mounted at the top of base 7 and surrounds the piston rod 9.

5 The vertical guide rods are braced and secured together in parallel, vertical relation at their upper ends by means of a top bar 13 which is vertically drilled to receive the ends of said rod. The two vertical guide rods with the top bar 13 form an upright standard or frame in which the several parts of the mechanism are mounted. A second stationary bar 14, traverses the vertical rods 11 and is rigidly connected therewith in vertical alignment with top bar 13.

15 Top bar 13 has journaled therein, a transverse horizontal stub shaft 15 which has fixed at one end, a driving pinion 16 and which may be revolved or oscillated by any suitable source of power, as by a motor or a hand crank C, fixed thereto.

10 The driving pinion 16 is in constant mesh with a bull gear 17 which is fixed to a stub shaft 18 journaled in the medial portion of the stationary bar 14. The stub shaft 18 projects through bar 14 and for some distance therebeyond and is keyed eccentrically to a gear 19 which is disposed on the front and opposite side of the frame or standard from the bull gear. The periphery of the gear 19 is thus disposed eccentrically of the axis of bull gear 17 and carries an outwardly and axially projecting pivot pin 20 to which the upper end of a connecting link 21 in the form of a heavy, metal bar, is journaled. A driven gear 22

25 has keyed thereto eccentrically thereof, a stub shaft 23 which is journaled in the cross head bar 10 connected with the upper end of the reciprocable piston rod. Gear 22 is of similar diameter and corresponds in number of teeth to the upper gear 19, which is meshed therewith and shaft 23 is connected eccentrically with gear 22

30 on a similar radius of eccentricity, as the connection between gear 19 and its stub shaft 18. Connecting link 21 is of a length to constantly retain gears 19 and 22 in mesh and is journaled at its lower end on a heavy pivot pin 24 disposed axially of gear 22 and journaled in a suitable bearing drilled in the lower end of said link.

Operation

35 When the bull gear 17 is revolved or oscillated through 180°, the eccentrically connected driving gear 19 is progressed from the position shown in Fig. 1 to the position shown in Fig. 3 and being intermeshed with the companion gear 22 eccentrically journaled on the vertical, slidable cross

head 10, imparts a straight line thrust upon the piston rod 9a, moving the same downwardly to the limit of its lower stroke shown in Fig. 3. Continued rotation of bull gear 17 or opposite oscillation thereof through 180°, returns the eccentrically mounted companion gears 19 and 22 to the position shown in Fig. 1, lifting the piston rod 9a with application of straight line lift longitudinally of the piston. In this connection, it will be noted that the axes of stub shafts 18 and 23 which eccentrically journal the companion gears 19 and 22 to the fixed bars 14 and slideable cross head respectively, extend in parallel relation in a common vertical plane which is coincident with the axis of piston rod 9. It will further be seen that the application of force and power to the reciprocable member, both in downward and upward strokes, is progressive and is smoothly accomplished without any jerkiness or marked pulsation, since the companion gears 19 and 22 are in constant mesh and since torque and eccentric principles are utilized rather than lever principles. Link 21 simply acts as a connection medium between the axes of the companion gears 19 and 22 serving to maintain said gears in mesh throughout the entire operation of the jack and in the upward or outward stroke of the plunger, transmitting the lift from the upper gear 19.

From the foregoing description, it will be noted that I have provided an exceedingly compact, powerful and highly efficient jack for reciprocating pump rods and other longitudinal elements.

With my novel structure, it will be noted that a double eccentric action is obtained through the interrelation of the two eccentrically mounted gears 19 and 22 and their intermeshed and link connection relation. Thus, the total reciprocating stroke obtained instead of being twice the radius of eccentricity of the mounting of one of the gears is nearly four times that radius. This multiplication of eccentricity resulting in a longer stroke is obtained without materially increasing the over-all housing space required and without materially increasing the power required.

It will further be seen that in the specific form illustrated, my structure lends itself to special attachment for well casings or cylinders with the base of the structure constituting a closure cap for the cylinder and with the guide rods 11 also constituting longitudinal members of the supporting frame. The several bars 13, 14 and 10 are interchangeable with the exception that in the case of the stationary bars 13 and 14, suitable means must be provided for rigidly securing the same to the appropriate portions of the upstanding guide rods 11, whereas the cross head or slideable carriage 10 must smoothly and loosely fit the said rods.

It will of course, be understood that various changes may be made in the form, details, arrangement and proportions of the parts without departing from the scope of my invention.

What I claim is:

1. A jack comprising a rotary member adapted to be connected for driving with either a source of rotary or oscillatory power, said rotary member having an axial shaft, a stationary member wherein said shaft is journaled, a power-converting gear wheel eccentrically affixed to said axial shaft and having an axially disposed pivot pin, a reciprocable member adapted to be connected to a longitudinally movable element to be driven, a stub shaft journaled in said reciprocable member and disposed parallel with the axial shaft of

said rotary member, a second gear wheel of similar diameter to said first mentioned gear wheel having its teeth in mesh with the teeth of said first gear wheel and fixed eccentrically to said stub shaft on a radius of eccentricity similar to that of said first gear wheel and a connecting link between said two gear wheels journaled at one end upon the axial pivot pin of said first gear wheel and journaled at its opposite end on an axial pivot pin affixed to said second gear wheel.

2. The structure set forth in claim 1, wherein the axis of said first mentioned rotary member and said stub shaft lie in a common plane substantially coincident with the approximate center of said reciprocable member.

3. A jack comprising a rotary member adapted to be connected for driving with either a source of rotary or oscillatory power, said rotary member having an axial shaft, a frame having a bearing in which said axial shaft is journaled, a power converting gear wheel eccentrically affixed to said axial shaft and having an axial pivot pin affixed thereto, a reciprocable member adapted to be connected to a longitudinally movable element to be driven, said frame having guides for said reciprocated member, a stub shaft journaled in said reciprocable member and disposed parallel with the axial shaft of said first mentioned rotary member, a second gear wheel of similar diameter to said first mentioned gear wheel having its teeth in mesh with the teeth of said first gear wheel and fixed eccentrically to said stub shaft on a radius of eccentricity similar to that of said first gear wheel and a connecting link between said two gear wheels journaled at one end upon the axial pivot pin fixed to said first mentioned wheel and journaled at its opposite end on an axially disposed pin fixed to said second wheel.

4. A jack having in combination a rigid frame comprising a pair of parallel guides, a reciprocating carriage mounted in said guides and adapted to be connected with a longitudinally movable element, a stub shaft journaled in said reciprocable carriage, a gear wheel eccentrically affixed to said stub shaft and having its body disposed perpendicularly to said shaft, a second stub shaft journaled in said frame at a point spaced outwardly of said first mentioned stub shaft with the axes of said shafts extending in a common plane disposed parallel with said guides, a second gear wheel affixed eccentrically to said second shaft and of similar diameter to said first gear wheel and intermeshed therewith, a link pivotally connected at one end to the axial portion of said first gear wheel and pivotally connected at its opposite end to the axial portion of said second gear wheel and means for driving said last mentioned shaft.

5. In combination with a cylindrical member having a longitudinally reciprocable element mounted therein, a jack having in combination a combined base and cap member secured axially to one end of said cylindrical member, a pair of parallel guides rigidly affixed at their ends to said base, a reciprocating carriage mounted in said guides and adapted to be connected with said longitudinally reciprocable element, a stub shaft journaled in said reciprocating carriage, a gear wheel eccentrically affixed to said stub shaft and having its body disposed perpendicularly to said shaft, said base and guides constituting portions of a rigid frame, a second stub shaft journaled in said frame at a point spaced outwardly of said first mentioned stub shaft with the axes of said shafts extending in a common plane disposed

parallel with said guides, a second gear wheel affixed eccentrically to said second stub shaft and of similar diameter to said first gear wheel and intermeshed therewith, a link pivotally connected at one end to the axial portion of said first gear wheel and pivotally connected at its opposite end to the axial portion of said second gear wheel and means for driving said last mentioned shaft.

6. The structure set forth in claim 5 and a bull gear affixed to said second stub shaft and means for driving said bull gear.
